United States Patent Office

Des. 181,485
Patented Nov. 19, 1957

181,485

ACOUSTIC TILE

Eve Murray, Hollywood, Calif., assignor to
K. G. Bierlich, Hollywood, Calif.

Application February 23, 1956, Serial No. 40,272

Term of patent 3½ years

(Cl. D18—2)

The figure is a top perspective view of an acoustic tile showing my new design.

I claim:

The ornamental design for an acoustic tile, substantially as shown.

References Cited in the file of this patent

UNITED STATES PATENTS

D. 59,476	Hoodwin	Oct. 25, 1921
D. 173,526	Erney	Nov. 23, 1954